UNITED STATES PATENT OFFICE.

EUGENE J. RAUCHFUSS, OF NEW YORK, N. Y., ASSIGNOR TO THEO. PABST & CO., OF SAME PLACE.

DESIGN FOR A DRINKING-GLASS.

SPECIFICATION forming part of Design No. 22,497, dated June 6, 1893.

Application filed April 25, 1893. Serial No. 471,836. Term of patent 7 years.

To all whom it may concern:

Be it known that I, EUGENE J. RAUCHFUSS, a citizen of the United States, and a resident of the city of New York, in the county and State of New York, have invented a new and original Design for Drinking-Glasses, of which the following is a specification.

In the accompanying drawing a side-view of a drinking glass provided with my new and original design is shown.

The leading feature of the design consists of a horizontal band of fleur de lis, in which the fleur de lis are arranged in two horizontal rows, the fleur de lis of the upper row projecting upward and those of the lower row projecting downward, and a border is formed above and below these two rows of fleur de lis.

A are the fleur de lis, B B are the top and bottom lines of each border, and C is a row of interlocking circles between each two lines B B.

Having thus described my invention, I claim as new and desire to secure by Letters Patent—

The design for a drinking glass, substantially as herein shown and described.

In testimony that I claim the foregoing as my invention I have signed my name in presence of two subscribing witnesses.

EUGENE J. RAUCHFUSS.
